UNITED STATES PATENT OFFICE.

THOMAS H. BOYD, OF OKLAHOMA CITY, OKLAHOMA, ASSIGNOR TO JAMES J. QUARLES AND WILLIAM H. AARON, BOTH OF PAWHUSKA, OKLAHOMA, COPARTNERS, TRADING AS GAS-TITE DEVICE COMPANY.

AUTOMATIC PRESSURE AND VACUUM DEVICE.

Application filed May 12, 1923. Serial No. 638,576.

To all whom it may concern:

Be it known that I, THOMAS H. BOYD, a citizen of the United States, residing at Oklahoma City, in the county of Oklahoma and State of Oklahoma, have invented 5 certain new and useful Improvements in Automatic Pressure and Vacuum Devices, of which the following is a specification.

The present invention has reference to 10 an automatic pressure and vacuum device for use on any and all containers of liquids of various kinds but more especially constructed for use on tanks or containers in which are carried or stored fluids containing 15 vapors or gas, such as crude or refined oil and gasoline.

The invention is designed primarily for 20 the purpose of maintaining a predetermined pressure in the tank or container of sufficient amount to retain the vapors, thereby increasing or retaining the quality of the fluid and reducing the evaporation loss to a minimum and is so constructed that it 25 functions either to relieve the tank of excess pressure or to admit air into the tank to fill the volume of space vacated by the liquid when the same is being discharged or drawn from the tank, the valves of the 30 device opening and closing automatically and without the human element of service entering into their operation, thereby eliminating all danger of blowing up, bursting or collapsing of the tank or container on 35 which the device is installed.

The invention further provides a pressure 40 and vacuum regulating device of the character set forth which is of generally improved construction and design, making the device very easy and economical to cast and machine and embodying, among other novel and advantageous improvements, a one-piece body casting having removable valve assemblies and fire-arresting means together with a dirt-and-moisture excluding cover 45 and an automatic drainage feature.

With the above and other objects in view, the invention consists essentially in the novel construction and combination of parts hereinafter more fully described and explained, 50 reference being had to the accompanying drawing illustrating the invention, wherein:

Figure 1 is an assembled view of the device with the parts shown in vertical section, and

Figure 2 is a section thru the body casting taken along line 2—2 of Figure 1.

The device is constructed of a one-piece body casting 10 enclosing the various chambers and provided with an internally threaded opening 11 at the extreme bottom for the 60 purpose of attaching the device to the tank or other container on which it may be used. The device is attached to tank by means of a short length of pipe screwed to bottom of casting and into flange secured to the 65 tank.

The opening 11 is the inlet thru which the chamber 12 of the casting receives the pressure of the tank and above this chamber is located the pressure exhaust chamber 13 in 70 the bottom wall 14 of which is provided an internally threaded port 15. Exhaust chamber 13 is open to the atmosphere at its upper end, as shown, and is equipped with a removable valve assembly including 75 a pressure valve 16 for automatically opening and closing port 15. Disposed laterally of the main or pressure receiving chamber 12 is an air intake chamber 17 having an internally threaded port 18 and being in 80 constant communication with chamber 12 by way of passage 19. Chamber 17 is also provided with a removable valve assembly; the same including a vacuum valve 20 for controlling the port 18. Chambers 13 and 85 17 are each provided with a suitable number of ribs 21, preferably four, to act as guides for the pressure valve 16 and vacuum valve 30, respectively. These ribs are 90 cast integral with the body casting and have stops 22 at their upper ends for limiting the extent of valve-opening movement, which stops may be formed by undercutting the ribs as shown.

The valve of each assembly is supported 95 on a valve seat 23 and has an integral depending portion 24 cast hollow and cone shaped with openings 25 in the sides to permit the free flow of gas or air to the bottom of the valve. The valve cone depends into the valve seat which is made cylindrical to permit the free movement of the cone at any angle thereby insuring return of the valve to a perfect seat. Each seat is, moreover, equipped with an exteriorly threaded portion 26 for attachment to the threaded ports 15 and 18 of the exhaust chamber and intake chamber, respectively.

tively, and with a locking collar 27 for abutment with the body casting to perfect an air-tight joint without the use of gaskets. In the body casting, directly over the vacuum valve 20, is an opening 28 for the purpose of attaching an instrument, such as a manometer, to determine the exact amount of pressure or vacuum under which the valves are functioning. The valves can 10 be constructed to act at any desired amount of pressure and the opening 28 provides convenient means for ascertaining if the valves act at the pressure intended. Being removable and of similar construction, the 15 valves are interchangeable and can be readily removed or replaced by applying a wrench to the wrench lugs 29 of the seats.

In the operation of the device the valves 20 open and close automatically. As the fluid within the tank evaporates, pressure is generated in the receiving and intake chambers 12 and 17 of the casting and is retained up to a certain amount. When the pressure exceeds the desired amount, valve 16 is thereby unseated and opens port 15 thru which the excess pressure escapes into the exhaust chamber 13 above, thence to the atmosphere; the valve reseating by gravity as the pressure lowers to the desired amount. Hence, 30 a predetermined amount of pressure is at all times retained in the tank, sufficient to retain the vapors and the quality of the fluid, thereby reducing the evaporation loss to the minimum. When the fluid is being 35 discharged or withdrawn from the tank a vacuum is created within chambers 12 and 17. This vacuum, which ordinarily hinders or prevents the free discharge of the fluid, is broken by the admission of air into the 40 device thru port 18; the valve 20 being opened automatically by the outside atmospheric pressure. The highest point at which either valve can raise under pressure will not allow lower or cone shaped part of valve 45 to go above seat, thereby insuring return of valve to the seat.

At the extreme top of the body casting and directly over the upper open end of the exhaust chamber 13 so as to be above the 50 pressure valve 16 is a cover 30 having sloping sides for shedding rain or moisture and for preventing dust or dirt from being deposited in or around the valve. Cast integral with the body casting is a drainage 55 chamber 31 having its upper end in communication with the exhaust chamber 13 so as to insure the drainage of any moisture that might be formed by condensation or by rain or snow blowing under cover 30 and tending 60 to clog or freeze the valve. The drainage chamber is, of course, open at its lower end and thus provides for the convenient and automatic drainage of the device.

Integrally connected to the cover 30 by 65 means of short depending lugs 32 is a flat

horizontal ring 33 adapted to rest upon the casting about the open end of the exhaust chamber 13 and serving to support the cover in raised position above the opening. Suitable fastening means, such as bolts 34, are 70 employed for removably securing the cover in place. Ring 33 also provides a retainer for a wire gauze 35 placed between the ring and the open end of the exhaust chamber. The gauze acts as a fire arrestor for preventing fire from entering the device in the event of the escaping gas becoming ignited. A cup-shaped screen, including a wire gauze 36 and a retaining ring 37, is provided for a similar purpose at the bottom opening of the drainage chamber; the ring being 75 screwed in a threaded counterbore of the chamber, as shown.

It will thus be seen that the device is both 80 fireproof and dripproof and that it is capable of being readily assembled or taken apart for repairs or inspection whenever desired. Moreover, the openings of the body casting are parallel to each other, making 85 the same easy to cast and machine. Valves and valve seats are to be made from materials not subject to corrosion or decay by atmosphere, or by any of the different fluids or gases that might be passed through the 90 device.

From the foregoing it is thought that the 95 construction and operation of the device will be readily understood and it is to be noted, in this connection, that the invention further embodies all such changes and refinements in 100 construction, design, etc., as are properly within the purview of the invention defined in the appended claims.

Having thus described the invention, what 105 is claimed as new and desired to be secured by Letters Patent is:

1. An automatic pressure and vacuum device comprising a pressure-receiving chamber, an air intake chamber communicating therewith, a pressure-exhaust chamber above the receiving chamber open at its upper end, valve means in the intake chamber operable to admit air into the receiving chamber, valve means in the exhaust chamber operable to permit escape of excess pressure from the receiving chamber, a wire gauze spanning the upper open end of the exhaust chamber, and a dirt-and-moisture excluding cover having a supporting ring engageable with said chamber for supporting the cover in raised position thereover, said ring also serving as a retainer for the said gauze. 110

2. An automatic pressure and vacuum device comprising a body portion having vertically aligned pressure-receiving and pressure-exhausting chambers respectively, said pressure-receiving chamber having an auxiliary intake chamber and said pressure-exhausting chamber having a drainage chamber, a cover mounted on the body portion in 115 120 125 130

raised position above the upper open end of the exhaust chamber, a fire-arresting screen removably engaged between the cover and the open end of the exhaust chamber, 5 and a fire-arresting screen removably engaged in the outer end of the drainage chamber.

3. In an automatic pressure and vacuum device, a one-piece casting having a main 10 or pressure-receiving chamber, an exhaust chamber positioned above the receiving chamber, a chamber disposed laterally of one side of the receiving chamber and providing

an air-intake chamber, a chamber disposed laterally of the opposite side of the receiving chamber and providing a drainage chamber for the said exhaust chamber, a retaining ring engaged with the outer open end of the exhaust chamber and a retaining ring engaged with the outer end of the drainage 15 chamber, the said ring of the exhaust chamber supporting a cover for the said chamber, and wire gauze between each retaining ring and chamber.

In testimony whereof I affix my signature.

THOMAS H. BOYD.
